DESIGN FOR A SMOKER'S ASHTRAY, OR SIMILAR ARTICLE

Allen G. Leiber, St. Louis County, Mo.

Application July 31, 1935, Serial No. 57,874

Term of patent 3½ years

To whom it may concern:

Be it known that I, Allen G. Leiber, a citizen of the United States, residing in Kirkwood, St. Louis County, in the State of Missouri, have invented a new, original, and ornamental Design for a Smoker's Ashtray, or Similar Article, of which the following is a specification, reference being had to the accompanying drawing, forming part thereof.

I claim:—

The ornamental design for a smoker's ashtray, or similar article, as shown.

ALLEN G. LEIBER.
